UNITED STATES PATENT OFFICE.

ELTON W. McCASLIN, OF CHICAGO, ILLINOIS, ASSIGNOR TO THE MORGAN & WRIGHT, OF SAME PLACE.

DESIGN FOR A SUPPLEMENTAL WHEEL-RIM.

SPECIFICATION forming part of Design No. 31,564, dated September 26, 1899.

Application filed August 21, 1899. Serial No. 728,031. Term of patent 14 years.

To all whom it may concern:

Be it known that I, ELTON W. McCASLIN, a citizen of the United States, residing at Chicago, county of Cook, State of Illinois, have invented and produced a new and original Design for Supplemental Wheel-Rims—that is to say, rims for converting rims of the clincher type into what are commonly known as "Crescent" rims—of which the following is a specification, reference being had to the accompanying drawings, forming part thereof.

In the said drawings, Figure 1 is a side elevation of the supplemental wheel-rim embodying my design. Fig. 2 is a cross-section of the same.

The outer side or surface of the supplemental wheel-rim is substantially concave in cross-section, being formed by a curved line or segment A. The inner side or surface may be regarded as a substantially flat surface provided with a central rib B, which is convex or substantially convex in cross-section. The side surfaces C C incline outwardly and overhang, substantially as shown in Fig. 2.

With such formation the transverse config-

ration or outline of the supplemental wheel-rim will consist of the aforesaid curved line or segment A, the upwardly-diverging side lines c c, and the curved line or segment b, it being observed also that the latter is connected at both sides with the aforesaid side lines c c by means of short horizontal or substantially horizontal lines c' c', substantially as shown in Fig. 2.

The essential feature of my design consists of the supplemental wheel-rim formed with an outer surface which is concave in cross-section, side surfaces which are inclined slightly outward, and the inner side or surface having a central rib which is convex in cross-section.

Having described my invention, what I claim as new, and desire to secure by Letters Patent, is—

The design for a supplemental wheel-rim substantially as herein shown and described.

ELTON W. McCASLIN.
